(57) **CLAIM**

The ornamental design for a flexible paint brush cover, as shown and described.

DESCRIPTION

FIG. 1 is a front perspective view of a flexible paint brush cover according to a first embodiment of the invention.

FIG. 2 is a front view thereof.

FIG. 3 is a rear view thereof.

FIG. 4 is a front view thereof shown in an open position.

FIG. 5 is a front view thereof shown in an open position shown in an environment of use.

FIG. 6 is a front view thereof shown in a closed position shown in an environment of use.

FIG. 7 is a rear view thereof shown in a closed position shown in an environment of use.

FIG. 8 is a front view shown in an open position according to a second embodiment.

FIG. 9 is a front view thereof, shown in an open position and in a second environment of use.

FIG. 10 is a front view thereof, shown in a closed position and in a second environment of use.

FIG. 11 is a rear view thereof, shown in a closed position and in a second environment of use.

FIG. 12 is a front view thereof, shown in an open position and in a third environment of use.

FIG. 13 is a front view thereof, shown in a closed position in a third environment of use; and,

FIG. 14 is a rear view thereof, shown in a closed position and in a third environment of use.

Broken lines are environmental only and form no part of the claimed design.

1 Claim, 10 Drawing Sheets
